(57) **CLAIM**

The ornamental design for a training station for use in the field of physiotherapy, as shown and described.

DESCRIPTION

1. Training station for use in the field of physiotherapy
1.1 is a perspective view showing the training station for use in the field of physiotherapy of my design;

1.2 is a front elevational view thereof;

1.3 is a rear elevational view thereof;

1.4 is a right side elevational view thereof;

1.5 is a left side elevational view thereof;

1.6 is a top plan view thereof; and

1.7 is a bottom plan view thereof.

The broken lines in the reproductions illustrate portions of the training station for use in the field of physiotherapy that form no part of the claimed design.
